MOP CLEANSING DEVICE

William E. La Mountain, Worcester, Mass.

Application February 10, 1951, Serial No. 210,400

2 Claims. (Cl. 15—257)

This invention relates to a device for aiding in cleaning dusting mops or similar articles subsequent to the intermittent use thereof.

One of the principal objects of the invention is to provide a device with which a dusting mop or similar article may be coupled and which will impart an intermittent jolting action to the mop when an oscillating motion is applied to the handle in a upward and downward direction whereby dust, dirt and the like may be dislodged from the head of the mop subsequent to intermittent uses thereof.

Another object is to provide a device of the above character which may be placed exteriorly of a window for coupling a mop therewith whereby the window may be thereafter moved to a nearly closed position, and dirt, dust or the like may be dislodged from the head of the mop while requiring the use of only one hand to manipulate the same and with less tendency of the dust reaching the operator.

Another object is to provide a device of the above character which will function as means for preventing injury to window sills, porch railings, or the like when dusting mops or similar articles.

Other objects and advantages of the invention will become apparent from the following description taken in connection with the accompanying drawings and it will be apparent that many changes may be made in the details of construction and arrangement of parts shown and described without departing from the spirit of the invention as expressed in the accompanying claims. I, therefore, do not wish to be limited to the exact details of construction and arrangement of parts shown and described as the preferred form only is given by way of illustration.

Referring to the drawings:

Fig. 1 is a perspective view of the device embodying the invention;

Fig. 2 is a sectional view of the device showing it in one position of use and further illustrating the function thereof; and

Figs. 3, 4 and 5 are enlarged fragmentary sectional views further illustrating the function of the device.

Referring more particularly to the drawings wherein like characters of reference designate like parts throughout the several views, the device embodying the invention is adapted to be placed exteriorly of a window or on a porch railing or the like in a readily accessible location whereby a dusting mop or similar article may be coupled therewith for imparting a jolting action to the mop through oscillation of the handle thereof whereby dust, dirt or the like may be dislodged from the mop subsequent to intermittent uses thereof. The said device embodies a base 6 having a groove 7 in its upper surface and having an upright 8 positioned to one side of said groove. The upright 8 is provided with an overhanging portion 9 having a groove 10 in its under surface and extending in the direction of the groove 7. The base 6 has substantially parallel ends and a dimension 11 of a length controlled to introduce a desired jolting action to the mop 12 when its handle is oscillated in an upward and downward direction as indicated by the arrows 13. The overhanging portion 9 is so controlled that the distance between its under surface and the upper surface of the base 6, as indicated by the arrows 14, is such as to provide a mouth portion of a width substantially equal to the diameter of the handle 12 and through which the handle may be inserted and coupled with the device

2

inwardly of the groove 7. The distance 14 is just slightly greater than the diameter of the handle. The distance between the bottom of the groove 7 and the bottom of the oppositely disposed groove 10 in the overhanging portion 9 is illustrated by the arrows 15, as best shown in Figs. 1, 3, 4 and 5, is so controlled as to provide sufficient clearance for enabling the desired jolting action to be imparted to the handle while requiring a relatively short oscillatory movement 13 of the free end thereof. 10 This distance 15 is substantially twice the diameter of the handle, and the width of the overhanging portion 9 is approximately or slightly less than one-third the length 11 of the base. The function of the device is substantially as follows: The mop from which dust, dirt or the like is to be dislodged from the head 16 thereof subsequent to intermittent uses thereof is placed inwardly of the mouth of the device to a position of rest within the longitudinal groove 7. If the device is placed on the sill of a window, such as illustrated diagrammatically at 15 17, the window 18 is moved to a partially closed position, allowing only sufficient space for the oscillating movement of the free end 19 of the handle, as illustrated best in Fig. 2. By imparting a brisk upward and downward oscillating motion to the free end 19 of the handle, the said handle will be caused to move to the various positions illustrated in Figs. 3, 4 and 5. It is particularly pointed out that when the mop is coupled with the device the distance between said device and the head of the mop is considerably greater than that of the distance 20 between the free end 19 of the handle from said device so that when only a slight oscillatory motion is imparted to said free end, the head will move through a considerably wider arc, as illustrated by the arrows 20.

Now referring more particularly to Figs. 3, 4 and 5, 25 it is pointed out that when the handle is in the related position shown in full lines in Fig. 3 and when a relatively rapid downward movement is imparted thereto, as illustrated by the arrow 13, the motion will tend to impart a bouncing movement to the handle whereby it 30 will first hit the base 6, at the rear edge 21 of the groove 7, causing the outer portion of the handle to move to a position illustrated by the dash lines 22, continued motion in this direction will next cause the handle to engage the forward edge of the groove 10, as illustrated at 23 35 in Fig. 4, while the said handle still rests upon the rear edge 21. Continued movement of the handle in the opposite direction, as illustrated by the arrow 13 in Fig. 4, will cause the handle to next engage with the outer edge 24 of the groove 7, as illustrated by the dash line 40 representation 25 of the handle. Continued movement 45 in this direction will next cause the handle to engage the rear edge 26 of the groove 10, as illustrated in Fig. 5, while the handle remains substantially in engagement with the edge 24. Continued movement in the opposite 50 directions, as illustrated by the arrow 13 in Fig. 5, will cause similar repetitive actions to take place.

By imparting a brisk upward and downward oscillating motion therefore to the handle 12, it will be caused to bounce while held in coupled relation with the device 55 and will cause the head 16 to receive intermittent joltings whereby dust, dirt and the like will be readily dislodged from the head. It is particularly pointed out that the device requires the use of only one hand of the operator, it is extremely simple and efficient in its construction and will function as protective means for preventing injury to the window sill or other means to which it is attached for ready use.

The device may be formed of any desirable durable materials and it is adapted to be attached to the window sill for other means through the use of suitable connection screws, bolts or the like 27 which are extended through suitable openings 28 provided in the base.

The dimensional characteristics of the device will depend, of course, upon the dimensional characteristics of the handle 12 and will be so controlled as to impart the above joltings of the head of the mop in the most efficient manner.

It is further pointed out that due to the fact that the window 18 may be moved to a nearly closed position, 60 dislodged dust, dirt or the like will be more positively prevented from being blown inwardly of the window if

the air currents should be such as to tend to bring about this result.

From the foregoing description, it will be seen that simple, efficient and economical means have been provided for accomplishing all the objects and advantages of the invention. It will be understood that the base may be formed to different shapes as desired while retaining the above described characteristics.

Having described my invention, I claim:

1. A device for dusting mops or similar articles comprising a substantially rectangular base having a relatively flat upper surface, substantially parallel opposed ends and a first groove in the upper surface thereof and normally related with said parallel ends and extending throughout the distance between said ends, an upright member on said upper surface to one side of said groove and having a portion overhanging said groove and the upper surface portion of the base on the side of the groove opposite the upright, said overhanging portion having a second groove in the undersurface thereof aligned with and extending in the direction of the first groove, said overhanging portion having a relatively flat undersurface spaced from and substantially parallel with the adjacent underlying upper surface portion of the base and communicating with the second groove, the distance between said relatively flat undersurface of the overhanging portion and the adjacent upper surface of the base being slightly greater than the diameter of the handle of the mop or similar article to be used therewith, the distance between the bottoms of said aligned grooves being substantially twice the diameter of the handle and the width of the overhanging portion in the direction of the grooves being slightly less than one-third the distance between the parallel ends of the base, said spaced relatively flat undersurface of the overhanging portion and the adjacent upper surface of the base providing an inwardly extending mouth portion in the direction of the plane of the upper surface of the base and the correlated dimensions of the base, the width of the overhanging portion, length of the respective grooves and aligned relation thereof and the parallel ends of the base all functioning cooperatively to produce the desired jolting action when the handle of the mop or similar article is placed in the device and manipulated upwardly and downwardly to dislodge particles of dust, dirt, etc., from the mop, the said oppositely disposed first and second grooves and the angle of disposition of the mouth portion further functioning cooperatively to retain the mop handle in desired positional relation with the device during the manipulation of the handle.

2. A device for dusting mops or similar articles comprising a substantially rectangular base having a rela-

tively flat upper surface, substantially parallel opposed ends and a first groove in the upper surface thereof and normally related with said parallel ends and extending throughout the distance between said ends, an upright member on said upper surface to one side of said groove and having a portion overhanging said groove and the upper surface portion of the base on the side of the groove opposite the upright, said upright having a substantially vertically disposed inner edge surface adjacent one side edge of the first groove and communicating with a second groove in the undersurface of the overhanging portion and aligned with and extending in the direction of the first groove, said overhanging portion having a relatively flat undersurface spaced from and substantially parallel with the adjacent underlying upper surface portion of the base and communicating with the second groove, the distance between said relatively flat undersurface of the overhanging portion and the adjacent upper surface of the base being slightly greater than the diameter of the handle of the mop or similar article to be used therewith, the distance between the bottoms of said aligned grooves being substantially twice the diameter of the handle and the width of the overhanging portion in the direction of the grooves being slightly less than one-third the distance between the parallel ends of the base, said spaced relatively flat undersurface of the overhanging portion and the adjacent upper surface of the base providing an inwardly extending mouth portion in the direction of the plane of the upper surface of the base and the correlated dimensions of the base, the width of the overhanging portion, length of the respective grooves and aligned relation thereof and the parallel ends of the base all functioning cooperatively to produce the desired jolting action when the handle of the mop or similar article is placed in the device and manipulated upwardly and downwardly to dislodge particles of dust, dirt, etc., from the mop, the said oppositely disposed first and second grooves and the angle of disposition of the mouth portion further functioning cooperatively to retain the mop handle in desired positional relation with the device during the manipulation of the handle.
